UNITED STATES PATENT OFFICE.

WILLIAM ROLAND SMITH, OF HILLSBORO, TEXAS.

GARTER.

Application filed May 11, 1926. Serial No. 108,331.

This invention aims to provide a simple means for mounting a garter on the leg of a wearer and for connecting the garter with a stocking or sock.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

20 In the drawings:—

Figure 1 shows in perspective, a device of the class described constructed in accordance with the invention;

Figure 2 is an elevation of the connector;

25 Figure 3 is a cross section on the line 3—3 of Figure 2;

Figure 4 is a section on the line 4—4 of Figure 2;

30 Figure 5 is a plan of the complete device with parts of the band broken away.

In carrying out the invention there is provided a U-shaped plate 1, which, possibly, has some resiliency, the plate 1 being curved transversely, as at 2, to shape it to the leg 35 of the wearer, the plate including arms 3 provided at their upper ends with inwardly extended flanges 4. The numeral 5 marks a band, which may be elastic, the band being

supplied at its ends with loops 6 which may be adjusted as to size by buckles 7, the loops 40 being engaged with the arms 3 and being held on the arms by engagement with the flanges 4, the flanges 4 being spaced apart by a slit 8 which, preferably, is narrow enough so that both of the loops 6 cannot be 45 slid at once off the arms 3. Any suitable means may be supplied for connecting the plate 1 to the sock or stocking 9. If desired, the plate 1 may be supplied on its inner edge, and at a point diametrically opposite 50 to the slit 8, with a downwardly extended hook 10 that slants toward the plate as the hook extends downwardly. The sock or stocking 9 is pulled upwardly and forwardly through the opening 11 in the plate 1 and 55 is caught on the hook 10, as shown in Figure 1.

What is claimed is:—

In a device of the class described, a U-shaped plate including arms provided at 60 their upper ends with inwardly extended flanges, and a band having loops detachably engaged with the arms and held on the arms by the flanges, the inner edges of the flanges being spaced apart by a slit which 65 is so narrow that the loops can be passed through the slit one at a time only, and means for connecting the plate to a stocking: the plate being convexed transversely 70 from side to side to conform to the surface of the leg of the wearer.

In testimony that I claim the foregoing as my own, I have hereto affixed my signature.

WM. ROLAND SMITH.
